DOUBLE ACTING PUMP FOR WELLS

George W. Walker, Golden Meadow, La.

Application August 19, 1937, Serial No. 159,962
Renewed August 25, 1939

1 Claim. (Cl. 103—156)

The present invention relates to double acting or double stroke pumps for use in pumping liquid in oil wells, water wells, or the like, and has for its principal object to provide a pump housing adapted to be lowered into the well together with the well tubing and forming a part of said tubing to position the pump at the most effective level of the well.

A further object is to provide a double acting pump of this character of simple and practical construction, which is efficient and reliable in performance, relatively inexpensive to manufacture and maintain in operative position, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the pump housing shown connected to the well tubing.

Figure 2 is a vertical sectional view therethrough.

Figures 3, 4, and 5 are transverse sectional views taken respectively on the lines 3—3, 4—4, and 5—5 of Figure 2.

Figure 6 is an enlarged fragmentary sectional view showing the pump cylinder and piston.

Figure 7 is an enlarged fragmentary sectional view of the upper chamber of the pump housing.

Figure 8 is a detail in section of the check valve for the upper end of the tube.

Figure 9 is a perspective view of one of the tubes; and

Figure 10 is a detail in section of one of the connectors for the rod coupling.

Referring now to the drawings in detail, wherein, for the purpose of illustration, I have disclosed a preferred embodiment of the invention, the numeral 5 designates a cylindrical pump housing including an intermediate section 6, upper and lower sections 7 and 8, respectively, and upper and lower reducing sections 9 and 10, respectively. Each of the above mentioned sections is connected by unions 11 having partitions 12 formed integrally therewith and separating the pump housing into chambers 13, 14, 15, 16, and 17, positioned in the order named from the top to the bottom of the casing, as will be apparent from an inspection of Figure 2 of the drawings.

A plurality of tubes 18 threaded in the uppermost partition 12 provide communication between the chambers 13 and 14, while a plurality of tubes

19 extend from the chamber 14 to the lowermost chamber 17; while a plurality of tubes 20 extend from the upper chamber 13 to the chamber 16 and a plurality of tubes 21 extend through the lowermost partition and provide communication between the chambers 16 and 17. 5

Each of the tubes is threaded at its upper end for threadedly receiving a valve seat cap 22 having a cage 23 extending upwardly therefrom for retaining a ball check valve 24 in position therein, 10 said ball check valves controlling communication through the respective tubes.

Each of the partitions is also provided with a central opening, the partitions defining the ends of the intermediate section 6 of the housing having the chamber 15 therein have threadedly connected thereto a pump cylinder 25 which extends entirely through the chamber 15 and provides communication between the chambers 14 and 16. The upper partition 12 has a guide cylinder or 20 tube 26 centrally positioned therein in vertical alignment with the pump cylinder 25, while the lowermost partition is provided with a central enlarged tube 27 having a check valve assembly 28 mounted in its upper end, the last named tube 25 providing communication between the chambers 16 and 17. 25

A piston 29 has a working fit in the cylinder 25 and has a piston rod 30 connected thereto extending upwardly through the guide tube 26. 30

The upper section 9 of the housing has a reduced neck 31 extending upwardly therefrom, and the lower section 10 of the pump housing has a similar neck 32 extending downwardly therefrom for connecting to the well tubing 33 by a union 34. The piston rod 30 is formed of sections connected to each other by a threaded coupling 35. The guide tube 26 is also provided with a packing 36 through which the piston rod 30 is slidably inserted. 35

In the operation of the device, when the pump housing is lowered in the well, a down stroke of the piston 29 will cause fluid in the chamber 16 to be forced upwardly through the tubes 20 past the check valve at the top thereof into the upper chamber 13. At the same time the down stroke of the piston will produce a vacuum in the chamber 14 causing the check valve at the top of the tubes 19 to open and drawing liquid from the lower chamber 17 upwardly into the chamber 14. 45 An up stroke of the piston 29 will produce a suction in the chamber 16 resulting in an opening of the check valve in the upper ends of the tubes 21 and 27 for drawing fluid upwardly from the chamber 17 into the chamber 16. Such upward 50

stroke of the piston will at the same time create a pressure in the chamber 14 forcing fluid therefrom upwardly through the tubes 18 into the chamber 13.

5 The several tubes connecting the various chambers may be in sections and connected by collars or sleeves, the tubes preferably being threadedly connected to the respective partitions. It will also be apparent that the piston may be pulled with the piston rod for repairs or replacement without the necessity of pulling the tubing or pump.

Having thus described the invention, what I claim is:

15 A double acting pump comprising a pump housing formed of a plurality of interconnected tubular sections, said housing including upper and lower end sections having reduced necks for attaching to a well tubing, a central intermediate

section and upper and lower intermediate sections at each end of the central intermediate section and interposed between the central intermediate section and the respective upper and lower end sections, partitions separating the sections and defining compartments in the housing, a pump cylinder open at each end and communicating with both of said upper and lower intermediate sections, a piston having a working fit in said cylinder, tubes providing communication with the upper intermediate section and the lower end section, tubes providing communication between the lower intermediate section and the upper end section, tubes providing communication between the respective upper and lower intermediate sections and the adjacent end sections and check valves for each of said tubes. 5 10 15
